DESIGN FOR A SHOE BUCKLE

Winifred L. Gibbons, Providence, R. I.

Application May 1, 1936, Serial No. 62,408

Term of patent 3½ years

To all whom it may concern:

Be it known that I, Winifred L. Gibbons, a citizen of the United States, residing at Providence, in the county of Providence and State of Rhode Island, have invented a new, original, and ornamental Design for Shoe Buckles, of which the following is a specification, reference being had to the accompanying drawing, forming part thereof.

In said drawing,

Fig. 1 is a front face view, and Fig. 2 is an edge view of a shoe buckle, showing my new design.

I claim:

The ornamental design for a shoe buckle, as shown.

Signed at Providence, in the county of Providence and State of Rhode Island, this twenty-second day of April, A. D. 1936.

WINIFRED L. GIBBONS.
